HAT

Engelbert J. Peham, St. Paul, Minn., assignor to Peham Plastics, Inc., St. Paul, Minn.

Filed Feb. 2, 1971, Ser. No. 112,094

Term of patent 14 years

Int. Cl. D2—03

U.S. Cl. D2—258

FIG. 1

FIG. 3

FIG. 5

FIG. 4

FIG. 2

FIG. 1 is a side elevational view of a hat, showing my new design, the other side being a mirror image of that shown;

FIG. 2 is a front elevational view, the rear side being a mirror image of that shown;

FIG. 3 is an enlarged fragmentary view thereof;

FIG. 4 is a sectional view on the line 4—4 of FIG. 3, and

FIG. 5 is a sectional detail on the line 5—5 of FIG. 3. The characteristic feature of my design resides in the brim portion of the hat.

I claim:

The ornamental design for a hat, as shown and described.
